BOTTLE

Ralph Morris, Westwood, N. J.

Application March 30, 1955, Serial No. 35,282

Term of patent 14 years

(Cl. D58—8)

Fig. 1 is a top plan view of a bottle, showing my new design.

Fig. 2 is a front elevational view thereof, showing the bottle cap removed from the bottle.

Fig. 3 is a side elevation of the bottle.

I claim:

The ornamental design for a bottle, as shown.
